US00D591165S

(12) **United States Design Patent**
Bradley et al.

(10) **Patent No.:** **US D591,165 S**
(b4) **Date of Patent:** **** Apr. 28, 2009**

(54) **DISPENSER**

(75) Inventors: **Christopher M. Bradley**, Orinda, CA (US); **John Jamieson**, Walnut Creek, CA (US); **Jeffrey Tilley**, La Honda, CA (US); **John C. Crawford**, Mahopac, NY (US)

(73) Assignee: **Colgate-Palmolive Company**, New York, NY (US)

(**) Term: **14 Years**

(21) Appl. No.: **29/318,708**

(22) Filed: **May 27, 2008**

Related U.S. Application Data

(63) Continuation-in-part of application No. 29/278,557, filed on Apr. 2, 2007, now Pat. No. Des. 576,039.

(51) **LOC (9) Cl.** **09-01**

(52) **U.S. Cl.** **D9/691**

(58) **Field of Classification Search** D9/682-694, D9/500-505, 516-575, 434-436, 447-450; 215/379, 382-384; 220/669-675; 222/209, 222/211-213, 215, 321.7-321.9, 372, 373, 222/378, 379, 383.1, 384-386, 398, 400.7, 222/400.8, 401, 402.1-402.25

(Continued)

Primary Examiner—Catherine Tuttle(74) *Attorney, Agent, or Firm*—Amy M. Fernandez(57) **CLAIM**

The ornamental design for a dispenser, as shown and described.

DESCRIPTION

FIG. 1 is a perspective view of the dispenser showing our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showing of the interior of the bottom of the container is for illustrative purposes only and forms no part of the claimed design.

1 Claim, 6 Drawing Sheets
